WEEDER OR THE LIKE

Thomas I. Mendenhall, 2508 S. Ridgeway Ave.,
Chicago, Ill.

Filed Jan. 18, 1960, Ser. No. 59,098

Term of patent 14 years

(Cl. D35—2)

FIGURE 1 is a top plan view of a weeder showing my new design with a portion of the handle being broken away for convenience of illustration; and

FIGURE 2 is a side elevational view thereof with a portion of the handle being broken away for convenience of illustration.

The characteristic features of my design for a weeder or the like reside in the rearwardly extending teeth of the weeder blade, as shown.

I claim:

The ornamental design for a weeder or the like, substantially as shown and described.
